UNITED STATES PATENT OFFICE.

WALTER J. WARDER, JR., OF CHICAGO, ILLINOIS; RUSSELL WARDER LIMBACH
ADMINISTRATOR OF SAID WALTER J. WARDER, DECEASED.

ARMATURE WINDING.

Application filed January 17, 1918. Serial No. 212,219.

To all whom it may concern:

Be it known that I, WALTER J. WARDER, Jr., a citizen of the United States of America, and a resident of Chicago, county of Cook, and State of Illinois, have invented certain new and useful Improvements in Armature Windings, of which the following is a specification.

This invention relates to dynamo-electric machinery, and especially to the armature circuits and circuit members of heavy current generators such as are used to supply current for electrolytic work.

In constructing armatures of the character stated, it is always desirable to economize conductor space under the poles, and to provide as many turns as possible in a given space. To this end it is necessary to work the inductive parts of the winding at as high a current density as may be consistent with permissible temperature. Hence, it is advantageous and has long been customary to use flat rods or ribbons set edgewise for conductors, and these have been disposed and connected in various ways, but always subject to heat limitations. Moreover they have been subject to more or less difficulty in forming and to waste of material in forming or to inefficient disposition of the conducting material.

The main objects of the invention are to provide an improved form of conductors for the armature coils and commutator connectors, and improved methods for making and assembling same; to provide such coils and connectors in simple forms adapted for machine manufacture and ready assemblage; to provide for efficient disposition of the conductor material; to provide improved and more economical methods and means for making large capacity windings adapted for high current density in generating part and rapid heat radiation in the connecting parts, and especially to make such windings from sheet metal by punching suitable conductor parts therefrom and connecting same together in due form; to provide sheet metal coils and complementary commutator connectors therefor, adapted for ready forming from punchings; to provide sheet metal punchings of suitable forms and with a minimum of waste material, adapted for bending sidewise into shape ready for use as armature coils and

commutator connectors; and to provide such conductors adapted to fit compactly in place when assembled to produce a perfectly balanced and symmetrical armature.

An illustrative embodiment of this invention is shown in the accompanying drawings in which—

Fig. 1 is an end view of one side of a double wound armature with the shaft shown in cross section, part of the winding being broken away and part of the circuit being shown diagrammatically.

Fig. 2 is a cross section through one of the armature slots.

Fig. 3 is a conventional diagram of part of one of the windings of the armature developed in a plane.

Fig. 4 is a side view of the armature with certain parts broken away to show the interior construction.

Fig. 5 is a perspective view showing part of one of the windings.

Fig. 6 is a fragmentary view of part of the armature as viewed from one side, the outer protective covering being removed.

Fig. 7 is a plan of one of the conductor punchings formed into shape ready to serve as an armature coil.

Fig. 8 is a plan of a punching ready for forming into a coil such as is shown in Fig. 7, the dotted lines representing a sheet metal blank and showing the relative position of the punchings struck therefrom.

Fig. 9 is a side view of the coil shown in Fig. 7.

Fig. 10 is an end view of the coil shown in Fig. 9 as viewed from the left.

Fig. 11 is a plan of an end connector punching for the commutator end of a coil.

In the illustrative embodiment shown in the drawings, a double wound armature 1 is provided with a pair of commutators 2 and 3 at the opposite ends respectively for the two windings 4 and 5. The armature core 6 is provided with a series of slots 7 distributed uniformly about its periphery, alternate slots 7' constituting one set being used for one of the windings 4 and the other slots 7'' being used for the second winding 5. The machine shown and described has ten poles 8 and said armature has fifty slots. Each of said commutators contains twenty-five segments 9 corresponding with the number of coils in each of said windings. Each coil comprises a single turn.

Each of the armature turns or coils comprises a loop part 10 the sides of which are adapted to fit in certain respective slots and an end connecting part 11 formed and 5 adapted for connecting the loops 10 to the commutator and to one another in continuous succession to make a closed circuit winding, the structure and shape of the coils being shown clearly in Fig. 5.

10 Each of the coil units or turns proper 10 consists of a punching 10' struck from a plate of suitable sheet metal, preferably copper, which punching is formed into shape by suitable bending, as hereinafter described. Each of said punchings is of L-shape in general form, and comprises a pair of L-shaped branches connected at the outer ends of the short arm, each of the short arms 12 being relatively wide as compared with the long slender arms 13. Said punching is formed into suitable shape for use as a coil loop by bending the two short arms sidewise in opposite directions from the plane of the connecting part 14, and at 25 or near the point where the long and short arms merge together the short arms are bent, as at 15, so as to dispose the long arms in planes which are substantially radial to the axis of the armature when set in place 30 thereon in the corresponding slots 7. As thus constructed, each coil comprises a pair of light and narrow inductively active conductors 13 adapted to fit in the slots 7 under the field poles 9, and a relatively broad 35 and heavy connecting part 14 having a large radiating surface. In bending the punching into shape the arms 13 are swung to such relative position as to be located 180 electrical degrees apart when assembled in 40 place, the precise form depending on the number of poles comprised by the field member. The L-shaped punchings 10' may be struck from a long, narrow strip of sheet metal, 16, the relative position of the punchings to the stock being illustrated in Fig. 45 8, where the numerals 16' and 16'' indicate the edges of said strip. One punching is shown in full lines, and the next adjacent punching is represented by dotted lines.

50 By this arrangement of punchings, great economy of material is effected, as there is very little waste of the high grade copper stock used.

The structure of the end connectors 11 is 55 comparatively simple. Said connectors are formed from plain U-shaped punchings 11', the arms 17 of which are bent away from each other on opposite sides of the plane of the connecting part 18. In order to facilitate connecting the adjoining ends of the coil loops and end connectors respectively, the ends of the latter are preferably forked, as at 19, to receive the corresponding ends 60 of the loop arms 13. For this purpose, each 65 connector may to advantage consist of a

pair of similar U-punchings 11' duly formed and fastened together face to face in laminated arrangement, with the outer ends of the corresponding arms 17 spread apart somewhat to provide the said fork 19. The 70 component layers of each arm of a connector are preferably riveted together adjacent to the fork as at 20.

Each of the commutator segments 9 is provided with a longitudinal slot 21 at or adjacent to its inner end for receiving the middle or body part 18 of each end connector 11. The said connectors are secured to the commutator segments by rivets 22 supplemented by solder. This is done before 80 the commutator segments are assembled, and the members 11 take the place of the tangs usually provided on commutator bars.

In assembling the armature parts, the coils or loop members 10 and the end connectors 85 11 are applied to the armature independently, and when fully assembled, are fastened together in series, preferably by soldering, or in such other manner as will provide good electrical contact. Corresponding branches 90 of all of the loop members 10, that is to say on one side, are disposed in the bottom parts of the slots 7, which are deep and narrow and the complementary arms are disposed in the outer parts of the corresponding slots 95 respectively. For instance referring to the upper part of Fig. 1, the left arm 13 of each loop of winding 4 is in the bottom of its slot, and the other arm is in the outer part of the fourth slot to the right. Each connector 100 11 has its right arm connected to an outer conductor in one slot, and its left arm to an inner conductor three slots to the left.

In forming the windings and applying same to the armature no edgewise bending 105 of the punchings is necessary, the shape of the punchings being such that sidewise bending of the end loops and connectors is sufficient to produce the required shape.

Insulation 23 is provided for each conductor, and the windings are held in place by any suitable locking means, such for instance, as a wedge member 24 illustrated in Fig. 2. The ends of the conductors 13 projecting beyond the sides of the core 6 and especially 110 the ends carrying the heavy cross-over parts or loop ends 14 are secured against centrifugal force by suitable binding means 25.

The coil parts 10 and 11 are herein described as made from "punchings," but corresponding strips formed by shearing, sawing, or otherwise may be used, and respecting the claims such strips are to be regarded as equivalents of punchings, though there are many advantages peculiar to the manufacture and use of actual punchings.

Although but one specific embodiment of the invention has been herein shown and described, it will be understood that numerous details of the construction shown may be 130

altered or omitted without departing from the spirit of this invention as defined by the following claims.

I claim:

- 5 1. An armature comprising two double layer windings with involute end connections adapted for connection to commutators upon opposite sides thereof, the coils of one winding having their connecting portions disposed in alternate slots relative to the slots housing the other winding and the involute end connecting portions of said windings being disposed in different planes.
- 10 2. An armature comprising two sets of

windings disposed upon a core and connected to commutators upon opposite sides thereof, the coils of one winding having their active portions disposed in one set of slots, and the coils of the other winding having their active portions housed in alternate slots, and the end connecting portions of said windings being disposed in endwise relation, thereby substantially preventing mutual induction in said end connections.

Signed at Chicago this 4th day of Jan., 1918.

WALTER J. WARDER, JR.
